H. HONEGGER.
WATCH CASING.
APPLICATION FILED DEC. 1, 1913.

1,128,873.

Patented Feb. 16, 1915.

UNITED STATES PATENT OFFICE.

HENRY HONEGGER, OF MILAN, ITALY.

WATCH-CASING.

1,128,873.

Specification of Letters Patent. Patented Feb. 16, 1915.

Application filed December 1, 1913. Serial No. 803,653.

To all whom it may concern:

Be it known that I, HENRY HONEGGER, a citizen of the Republic of Switzerland, residing at 14^a Via Dugione, Milan, Italy, have 5 invented new and useful Improvements in Watch-Casings; and I do hereby declare the following to be a full, clear, and exact description of the invention, such as will enable others skilled in the art to which it 10 appertains to make and use the same, reference being had to the accompanying drawing, and to letters or figures of reference marked thereon, which form a part of this specification.

15 This invention has reference to certain improvements in watch casings and it relates more specifically to a watch casing having two covers and a spring-ring, which connects the two casing parts together in 20 closing thereby the watch-work.

Two modes of carrying the invention into effect are shown by way of example in the accompanying drawing in which—

Figure 1 is a section on the line A—B of 25 Fig. 3. Fig. 2 is a section substantially corresponding to Fig. 1 showing one of the covers in its open position, Fig. 3 is a front view, partly in section of the watch, Fig. 4 shows a detail, Figs. 5 and 6 show 30 details of a second modification, and Figs. 7, 8 and 9 show details of a third modification.

1 denotes the watch-work provided with a projecting shaft 2. This shaft carries a 35 crown 3 for winding up the watch and adjusting the hands. The watch-work is surrounded by a dust-ring 4 serving to hold said work in the casing.

5 and 6 denote two covers, the cover 6 40 being arranged on the same side as the watch-dial and carrying an inserted glass piece 7. Each of the covers 5 and 6 has a flange 8. These flanges are of such a shape that they can inclose in their closed position the watch work. In this case the flanges 8 touch each other. The covers 5 and 6 have projections 9 forming in the closed position of the covers a pendant-like body surrounding the shaft 2. Upon the

50 shaft 2 is loosely mounted a body 10 having a cylindrical central part and tapering toward its ends. The projections 9 are provided with extensions 11 corresponding in shape to the body 10 and confining between them in the closed position of the covers an

open space. Said extensions 11 have also grooves 12.

13 is a spring-ring provided with a groove 14 having the same width as the two adjoining flanges 8. This ring 13 is further provided at its upper end with a circular opening 15 (Fig. 4) through which passes the sleeve formed by the projections 9, said ring being split at this place. If the covers 5 and 6 are in their closed position, the spring-ring 13 keeps them in said position, after the latter is put around the flanges 8.

16 denotes caps pressing the parts 11 against the body 10. The caps 16 are held by the stirrup 17 in the proper position 70 relatively to the parts 11.

For the purpose of opening the casing formed by the covers 5, 6 the spring-ring 13 is detached from said covers. Hereupon the covers are moved apart, or they may be opened, as illustrated in Fig. 2, only one cover, the cover 5 pivots around the body 10. In the construction shown in these figures the crown 3 is arranged inside the stirrup 17. As shown in Figs. 5 and 6 the crown may, however, as well be arranged below the stirrup 17. According to this modification the upper part of each projection 9 is ring-shaped and to these projections 9 are rigidly connected the parts 80 11 corresponding in shape to the body 10, which in this case forms a shaft (see dotted lines in Fig. 5). 16 denotes again the caps holding together the two covers and 17 is the stirrup. 18 is an adjustable screw 85 screwed into the shaft 10 and holding the latter in its proper position. In Figs. 7, 8 and 9 there is shown another form of the body 10 and of the pendant. This form of the body 10 secures a better fitting of the 90 crown. According to this modification only the extension 11 corresponding to the cover 5 is provided with a groove 12.

A watch casing according to this invention has no hinges or joints projecting beyond the casing and it may be closed in a sure and dust-tight manner.

I claim:

1. A watch case comprising two covers, the edges of which contact in the closed position of the covers, each cover having an integral channeled extension, the edges of the extensions being in the planes of the edges of the covers, said extensions combining to form a pendant-like hollow body in 110

- their closed position, a body entirely inclosed by the extensions and forming a pivot for the covers, and means to hold the latter in closed position.
5. 2. In a watch casing, two covers each having a flange thereon, a spring-ring surrounding said casing parts and having a groove of a width equal to the whole width of said flanges and capable of taking up the latter when the covers are in their closed position to hold them in said position.
10. 3. In a watch casing, two covers each having a flange thereon, an extension on each cover, a body surrounded by said extensions and provided with a hole for the shaft serving for winding up the watch and for adjusting the hands, means for holding said body in its proper position, a spring-ring surrounding said casing-parts and having a
15. 4. In a watch casing, two covers each having a flange thereon, an extension on each cover rigidly connected to the latter, and forming together in the closed position of the covers a pendant-like body, a body surrounded by said extensions and provided with a hole for the shaft serving for winding up the watch and for adjusting the hands, means for holding said body in its proper position, a spring-ring surrounding said casing-parts and having a groove of a width equal to the whole width of said flanges and capable of taking up the latter when the covers are in their closed position to hold them in said position.
20. 5. In a watch casing, two covers each having a flange thereon, an extension on each cover rigidly connected to the latter, and forming together in the closed position of the covers a pendant-like body, a body surrounded by said extensions and provided with a hole for the shaft serving for winding up the watch and for adjusting the hands, means for holding said body in its proper position, a spring-ring surrounding said casing-parts and having a groove of a width equal to the whole width of said flanges and capable of taking up the latter when the covers are in their closed position to hold them in said position.
25. 6. In a watch casing, two covers each having a flange thereon, an extension on each cover rigidly connected to the latter, and forming together in the closed position of the covers a pendant-like body, a body surrounded by said extensions and provided with a hole for the shaft serving for winding up the watch and for adjusting the hands, means for holding said body in its proper position, a spring-ring surrounding said casing-parts and having a groove of a width equal to the whole width of said flanges and capable of taking up the latter when the covers are in their closed position to hold them in said position.
30. 7. In a watch casing, two covers, means for holding the latter in their closed position, an extension on each cover forming together in the closed position of the covers a pendant like body, a body provided with a hole for the shaft serving for winding up the watch and for adjusting the hands and arranged with said extensions and acting as a pivot for the covers, means for pressing the extensions against the body acting as a pivot, and a stirrup holding said means in the proper position relatively to said exten-
35. 8. In a watch casing, two covers each having a flange thereon, an extension on each cover rigidly connected to the latter, and forming together in the closed position of the covers a pendant-like body, a body surrounded by said extensions and provided with a hole for the shaft serving for winding up the watch and for adjusting the hands, means for holding said body in its proper position, a spring-ring surrounding said casing-parts and having a groove of a width equal to the whole width of said flanges and capable of taking up the latter when the covers are in their closed position to hold them in said position.
40. 9. In a watch casing, two covers each having a flange thereon, an extension on each cover rigidly connected to the latter, and forming together in the closed position of the covers a pendant-like body, a body surrounded by said extensions and loosely mounted on a shaft projecting beyond the watch-work and serving for winding up the
45. 10. 5. In a watch casing, two covers each having a flange thereon, an extension on each cover rigidly connected to the latter, and forming together in the closed position of the covers a pendant-like body, a body surrounded by said extensions and having a groove of a width equal to the whole width of said flanges and capable of taking up the latter when the covers are in their closed position to hold them in said position.
- watch and adjusting the hands, caps press-
ing said extensions against this last men-
tioned body, a spring-ring surrounding said
casing-parts and having a groove of a width 50
equal to the whole width of said flanges and
capable of taking up the latter when the
covers are in their closed position to hold
them in said position.
6. In a watch casing, two covers each hav-
ing a flange thereon, an extension on each
cover rigidly connected to the latter, and
forming together in the closed position of
the covers a pendant-like body, a body sur-
rounded by said extensions and loosely 55
mounted on a shaft projecting beyond the
watch-work and serving for winding up the
watch and adjusting the hands, caps press-
ing said extensions against this last men-
tioned body, a stirrup holding said caps in 60
their proper position relatively to this body,
a spring-ring surrounding said casing-parts
and having a groove of a width equal to the
whole width of said flanges and capable of
taking up the latter when the covers are in 65
their closed position to hold them in said po-
sition.
7. In a watch casing, two covers, means
for holding the latter in their closed posi-
tion, an extension on each cover forming to-
gether in the closed position of the covers a 70
pendant like body, a body provided with a
hole for the shaft serving for winding up the
watch and for adjusting the hands and ar-
ranged with said extensions and acting as a 75
pivot for the covers, means for pressing the
extensions against the body acting as a
pivot, and a stirrup holding said means in
the proper position relatively to said exten-
sions.
8. In testimony that I claim the foregoing
as my invention, I have signed my name in
presence of two subscribing witnesses.
HENRY HONEGGER.
